(57) **CLAIM**

The ornamental design for a reservoir piezo disk assembly for a nebulizer, as shown and described.

DESCRIPTION

FIG. 1 is a perspective view of a reservoir piezo disk assembly for a nebulizer showing our new design;

FIG. 2 is a back view thereof;

FIG. 3 is a front view thereof;

FIG. 4 is a left view thereof;

FIG. 5 is a right view thereof;

FIG. 6 is a bottom view thereof; and,

FIG. 7 is a top view thereof.

Broken lines in the drawings depict portions of the reservoir piezo disk assembly for a nebulizer that form no part of the claimed design.
